Specification for Design.

Patented Jan. 14, 1919.

Application filed May 28, 1917. Serial No. 171,594. Term of patent 14 years.

To all whom it may concern:

Be it known that I, JOHN W. MAGUIRE, a citizen of the United States, residing at Chicago, in the county of Cook and State of Illinois, have invented a new, original, and ornamental Design for a Tire, of which the following is a specification, reference being had to the accompanying drawing, forming a part thereof, in which—

Figure 1 is a perspective view of a complete tire showing the design;

Copies of this patent may be obtained for five cents each, by addressing the "Commissioner of Patents, Washington, D. C."

Fig. 2 is an enlarged plan view of a section of a tire showing the design.

I claim:

The ornamental design for a tire, as shown.

JOHN W. MAGUIRE.
